UNITED STATES PATENT OFFICE.

JOHN CARLSON, OF PORTLAND, OREGON.

MORTISING-MACHINE.

1,096,599.

Specification of Letters Patent. Patented May 12, 1914.

Application filed December 21, 1911. Serial No. 887,083.

To all whom it may concern:

Be it known that I, JOHN CARLSON, a citizen of the United States, and a resident of the city of Portland, county of Multnomah, and State of Oregon, have invented certain new and useful Improvements in Mortising-Machines, of which the following is a specification.

My invention relates to improvements in mortising machines and more particularly to the so-called "hand" mortising machines, and has for its object the production of a machine of this character through the medium of which a hole of rectangular, square, or other polygonal form may be formed as readily as a circular hole.

A further object is the production of a machine of this character which will be of durable and economical construction, one which may be readily and easily manipulated, and one which will be of high efficiency in use.

Other objects will appear hereinafter.

With these objects in view my invention consists in the combinations and arrangements of parts hereinafter described and claimed.

My invention will be more readily understood by reference to the accompanying drawings forming a part of this specification, and in which—

Figure 1 is a front elevation of a mortising machine embodying my invention, Fig. 2 is a side elevation thereof, Fig. 3 is a transverse section taken on substantially line X—X of Fig. 1, and Fig. 4 is an enlarged sectional detail side elevation of the cutter chain and the support therefor.

The preferred form of construction as illustrated in the drawings comprises an inverted substantially U-shaped frame 1 having the parallel side members 2, said frame being formed preferably of metal. The side members 2 are reinforced at intervals by cross pieces 3 which extend between the same at the rearward edges thereof, a handle or grip 4 being provided at the upper end of the frame rigidly secured thereto.

Slidably mounted between the side members 2 of the frame 1 is a carrier consisting of the parallel side pieces 4 and the transversal connecting bars 4' which rigidly connect the members 4. The latter are provided at their outer sides with dove tail tongues 5 which slidably engage correspondingly

formed grooves 5' provided for the reception thereof in the adjacent inner sides of the frame members 2, as clearly shown in Fig. 3. Rotatably mounted in the carrier at the lower end thereof is a shaft 6, the latter being of a sectional character comprising preferably 3 sections, the inner ends of the outer sections being detachably connected at 7 with the respective ends of the central section, as clearly shown in Fig. 1.

Arranged medially between the lower ends of the frame side members 2 is an elongated bar 8 consisting of two sections which are adjustably connected by means of the double screw 9, the latter affording means for effecting longitudinal adjustment of said bar, as will be readily understood. The upper end of said bar 8 loosely embraces the central section of the shaft 6, the lower end of said bar being positioned between the U-shaped guide members 10 which embrace the lateral edges of said bar, said guide members being adjustably secured in proper position by means of threaded stems 11 which are threaded in the frame members 2 at the lower ends thereof, as clearly shown in Fig. 1, the outer ends of said stems being provided with heads for effecting ready rotation and hence adjustment of said guide members. The arrangement is such, as will be observed, that the bar 8 will be held centrally between the frame sides 2, free longitudinal movement thereof being however permitted. Arranged at the upper end of the bar 8 and mounted upon the shaft 6 is a sprocket wheel 12, said end of said bar being bifurcated to accommodate said sprocket wheel. Mounted at the bifurcated lower end of said bar is another sprocket wheel 13 around which the sprocket wheel 12 passes a sprocket chain 14. The arrangement is such, as is evident, that feeding of the sprocket chain is effected by rotation of the shaft 6, the longitudinal adjustment afforded the support-forming bar 8 being adopted in order to take up the slack in said chain. Mounted upon and projecting from the chain 14 at intervals are cutter blades 15, preferably of the peculiar form shown. All of said cutter blades are of identical form and dimensions, the same being adapted upon rotation of the chain 14 and upon the feeding or bodily downward movement of said chain to cut the surface 110

with which or into which the lower end of said chain is brought into contact to effect the formation of a hole corresponding in form with that of the cutting edges of said 5 blades, said plates, because of the peculiar construction thereof, being adapted to effectually perform this cutting.

Rotatably mounted in the upper end of the carrier is a transversely extending shaft 10 upon one end of which is carried a pinion 17 meshing with a rack 18 formed upon the adjacent edge of the adjacent frame member 2. This arrangement is such that the rotation of the shaft 16 imparts a similar motion 15 to the pinion 17 and causes a longitudinal movement of said carrier within the frame 1, the rotation of the pinion co-operating with the rack 18 to create this motion. Rotatably mounted in said carrier intermediate 20 the shafts 6 and 16 is a transversely extending counter shaft 19. The shaft 19 is operatively connected with the shaft 16 by means of a sprocket chain 20 which passes round coplanar sprocket wheels 21 and 22 25 mounted respectively upon said shafts. One end of the shaft 19 projects laterally from the frame 1, a gear 23 being mounted thereon. Said gear 23 meshes with a pinion 24 carried upon the corresponding laterally 30 projecting end of the shaft 6, so that rotation of said shaft will be effected upon rotation of said gear. Secured to the gear 23 is a crank handle 25 whereby said gear may be readily manually rotated. The construction 35 is such then as will be seen that an operative connection is established between the crank handle and the shafts 6 and 16 and so that, upon rotation of said crank handle, rotation of the cutter chain 18 and movement thereof bodily longitudinally of the frame 1 will be simultaneously effected.

In using the tool, the handle 4^a thereof is 40 grasped by one hand and the handle 25 by the other. The lower end of the tool is then 45 positioned and held securely against the surface in which the mortise is to be formed and the handle 25 rotated in the proper direction. Upon rotation of said handle the cutter blades will be brought into engagement 50 with the adjacent surface effecting the cutting thereof as desired. By reason of the sectional construction of the shaft 6 the sprocket chain and the parts connected therewith may be readily disconnected from 55 the device by disconnection of the central section of said shaft, so that a cutter of another form or dimensions may be employed if desired.

A mortising device of the construction set 60 forth is simple and economical in construction, the same is compact so that the same

may be readily carried about in a tool chest, and the same is efficient in operation.

While I have illustrated and described the preferred construction for carrying my 65 invention into effect this is capable of variation and modification without departing from the spirit of the invention. I therefore do not wish to be limited to the exact details of construction set forth but desire 70 to avail myself of such variations and modifications as come within the scope of the appended claims.

Having described my invention what I claim as new and desire to secure by Letters Patent is:

1. In a device of the class described, a main frame, a carrier slidably mounted therein, a bar carried by said carrier, sprocket wheels arranged adjacent the ends 80 of said bar, a cutter chain arranged on said wheels, means for imparting motion to said chain and means for guiding the lower end of said bar, said means comprising U-shaped jaws adapted to engage the opposite sides 85 of said bar, and stems on said jaws threaded into the opposite sides of the lower end of said frame.

2. In a device of the class described, a frame, a carrier slidably mounted in said frame, a shaft rotatably mounted in said carrier and comprising a pair of end sections journaled in said carrier and a central detachable section, a sprocket wheel fixed to said central section, a bar having a perforated end embracing the central section of said shaft adjacent said wheel, a second sprocket wheel arranged at the free end of said bar, a cutter chain arranged on said wheels and means for imparting motion to 100 said shaft, substantially as described.

3. In a device of the class described, an inverted U-shaped frame, a carrier slidably mounted therein, a shaft rotatably mounted in said carrier, means for imparting rotation to said shaft, a sprocket wheel on said shaft, a bar having a perforated end embracing said shaft, a sprocket wheel arranged adjacent the free end of said bar, and a laterally adjustable guide for the 110 lower end of said bar comprising a pair of U-shaped jaws adapted to embrace the sides of said bar, and stems on said jaws threaded into the lower ends of said U-shaped frame, substantially as described.

In testimony whereof I have signed my name to this specification in the presence of two subscribing witnesses.

JOHN CARLSON.
